UNITED STATES PATENT OFFICE.

OLE O. STORLE, OF MILWAUKEE, WISCONSIN, ASSIGNOR OF ONE-HALF TO
JOHN H. GORDON, OF ROCHESTER, NEW YORK.

GRAIN-BINDER.

SPECIFICATION forming part of Letters Patent No. 404,508, dated June 4, 1889.

Application filed January 14, 1884. Serial No. 117,441. (No model.)

To all whom it may concern:

Be it known that I, OLE O. STORLE, of Milwaukee, in the county of Milwaukee and State of Wisconsin, have invented certain new and 5 useful Improvements in Grain-Binders, of which the following is a full description, reference being had to the accompanying drawings, in which—

Figure 1 is a side elevation of the cord-holding, knotting, cutting, stripping, and tucking devices as seen from the stubble side of a self-binding harvester. Fig. 2 is a front view of the same parts. Fig. 3 shows the same parts as Fig. 2 as seen from beneath. Fig. 4 shows the cam and gear wheel for giving motion to all of the moving parts enumerated above. Fig. 5 is a perspective view of the knotter-frame. Fig. 6 is a side view of the segmental cam and gear wheel in section. Fig. 7 is a sectional view of the segmental cam and gear wheel, the disk of the same being removed to show the tucker and the contour of the cam-groove for moving it. Fig. 8 is a front view of the parts shown in Fig. 7. Fig. 9 is a perspective view of the tucker. Fig. 10 shows the tucker in position for acting as a stop to retain the twine in position on the knotter. Fig. 11 shows the position of the tucker-finger after having delivered the twine to the knotter.

The object of my invention is to perfect the band-uniting mechanism, and its nature will be hereinafter fully pointed out.

My devices, as shown, are adapted to the 35 form of binder having a frame shaped like the letter **U** on its side, in the arms of which are bearings for the knotter-driving shaft and needle-shaft, as shown in various patents.

In the drawings, A is the knotter-driving 40 shaft, having keyed to it on either side of the knotting mechanism the discharge-arms A'A². Keyed to this shaft is the miter-gear A³. Supported loosely on this shaft, so as not to be revolved by it, is the knotter-frame B. (Shown 45 in perspective in Fig. 5, where B' is a sleeve which forms a bearing on the shaft A.)

B² is an arm thrown out to assist in supporting the breast-plate.

B³ are holes through which screws pass to 50 secure the knotter-shaft bearing to the frame.

B⁴ is a stud on which the cord-holding disk is supported and revolves.

B⁵ is a sleeve in which the shaft of the tucker rocks.

B⁶ is a recess formed by the casing B', in 55 which the miter-gear L⁸ on the segmental cam and gear wheel revolves.

B⁸ is a casing for the miter-gear A³.

C, Fig. 6, is a stout cylindrical stud provided with the head C' and threaded at C³, 60 where it is screwed tightly into the frame B.

E is the breast-plate, secured to the frame by the rivets E', passing through the head of the bolt C, and by the screws E² through the 65 arm B².

F is the knotter, consisting of two jaws—one fixed, the other movable—on a knotter-shaft F', revolving in the sleeve D. To this shaft is keyed the pinion F². The knotter-shaft is slotted through to receive the movable jaw, so that the point F⁵ of the pivoted jaw of the knotter will bear against the end of the fixed jaw. The movable jaw at its heel is provided with the anti-friction roller F⁴. The end of the sleeve D, where contiguous to the knotter-jaws, is so shaped as to form a cam to open the pivoted knotter-jaw and to permit it to close as the roller on its pivoted jaw passes under the cam-shaped block G, mounted upon the end of the spring 75 G', which is secured to the sleeve D at G².

The construction of the knotter and the mechanism for opening and closing the jaw and the operation in tying the knot are well known and need not be more minutely described.

Upon the stud B⁴, I place the cord-holding disk H, (see Figs. 3 and 6,) which, as far as the construction and operation are concerned, differs little from some in common use; but 90 in the matter of driving and retaining in position it differs materially, as will now be explained. Cast as one piece with the disk is a pinion having six teeth, or any number that shall correspond with the number of notches 95 in the periphery of the holding-disk, which teeth are beveled, so as to properly engage with a tooth or teeth of a bevel-segment. H' are extensions of the teeth of this pinion, which extend from the body of the pin- 100

ion toward the axis of the cam and gear wheel—that is, stich is the general direction. As far as the extensions H' of the teeth H^2 are concerned, the pinion is in form a pin-wheel. 5 The holding-disk H occupies such position relative to the knotter that the twine carried by the needle will, when laid across the knotter-jaws, be also laid into the proper notch in the disk. Coacting with the notched disk is the holder plate or shoe I , grooved to permit the disk to revolve therein, the edges of the metal forming the sides of the grooves being so curved and smoothed that the twine carried by the disk in its rotation shall not be treated harshly. 15 The holder plate or shoe is pivoted at I' to the sleeve D and is elastically held in contact with the disk by the spring I^2 .

Referring to Fig. 1, the breast-plate is shown to have the slot E^3 for the passage of the needle in its movement to lay the twine on the jaws of the knotter. At its lower end near the knotter the slot is extended laterally and given the peculiar form shown at E^4 . The purpose of this lateral extension of the slot will be fully described when describing the discharge of the knot from the knotter; but in this connection it is stated that provision must be made for keeping the twine, when laid across the jaws of the knotter as 25 in Fig. 1, from escaping through the slot. Supported in the sleeve B^5 is the short rock-shaft J , to one end of which the tucker is firmly secured. To the opposite end of this shaft is secured the short arm J' . The short 30 arm is provided with an anti-friction roller J^3 , which moves in the cam-groove in the knotter-operating wheel. (Shown in Fig. 7.) The tucker-arm is so bent as to reach for a distance in a direction parallel with its axis of 35 vibration, and is then bent so as to lie flatwise beside the breast-plate, as seen in Figs. 7, 8, and 9. The position of the shaft of the tucker and its length are such that its operating-point J^4 shall move so close to the needle 40 as it brings the twine around the gavel that it may take the same and depress it to a position within reach of the knotter-jaws, as 45 shown in Fig. 11.

In Fig. 7 the needle is shown in section and 50 the twine in relation thereto in that part of its movement in which it is when the point J^4 of the tucker sweeps in the path indicated by the broken lines to engage the twine. I provide the tucker-arm with the supplemental finger J^5 in such a position that when the tucker is at rest the finger shall occupy the 55 position shown in Fig. 10, where it is seen to be thrust across the slot E^4 in the breast-plate; and the twine is prevented from escaping the knotter. A third position is given 60 the tucker for an instant—namely, that shown in Fig. 1—where it is thrown upward so far as to be fully withdrawn from crossing the slot, so that the knot stripping or discharging device may be at liberty to remove the completed knot by carrying the twines into the 65 slot E^4 .

K is an arm free to revolve on the stud-bolt C , and adapted to rotate close to the breast-plate on a plane parallel thereto, and 70 its extremity K' of such length as to sweep by the end of the knotter between the latter and the breast-plate and to overreach the width of the slot E^4 . This arm is preferably made of steel, and has as one piece with it 75 the knife K^2 , its blade bent abruptly to a plane at or near a right angle to the arm K' and of such length and radial sweep as to pass between the cord-holding disk and the knotter. 80

The operating parts have so far been treated but singly. The mechanism for giving them movement in the proper directions and at the proper relative intervals will next be considered, and the respective operations and the 85 coaction of all of the elements of the invention explained.

As already stated, the stud-bolt C serves as means for connecting the breast-plate to the frame. Besides this it serves as an axle for 90 which the segmental cam and gear wheel for giving the parts motion may revolve.

Referring now to Fig. 6, L is a sleeve free to revolve on the bolt C , and having as one piece with it the following parts: L' is a thin 95 disk concentric for nearly its whole circumference, and its periphery adapted to slide on the delay-surface F^6 on the knotter-pinion formed by cutting the flange of the latter to conform to the same. At the point where the 100 periphery of the disk is cut away to permit the flange of the pinion to roll, and abutting against such space, are the teeth L^2 of the segmental cam and gear wheel which operates the knotter, of such number, radius, and 105 pitch that they may engage with the teeth of the knotter-pinion and give the latter one rotation. At the ending thereof the completed part of the periphery again strikes beneath the delay-surface of the pinion and locks it. 110

Upon the side of the disk L' nearest the breast-plate E , I arrange two flanges L^3 and L^4 , of proper width to form a cam-groove that shall permit the roller J^3 to travel therein and give it proper breadth of tread. These flanges 115 are, at all parts of the wheel, parallel, and the contour of the channel formed by them such as shown in Fig. 7, where it is seen that for the greater part of the circumference (that part numbered 1) it is concentric, and 120 hence during the greater part of the revolution of the wheel the tucker-finger moved thereby will remain in one of the three positions longer than any other. This position is that shown in Fig. 10, where, as already 125 explained, the escape of the twine from the knotter is prevented by the finger J^5 resting across the slot E^4 .

In the movement of the binder the needle soon reaches a certain position and the tucker 130 is required to engage the twine and carry it positively to the knotter by a downward sweep. To give the tucker this movement, I give the cam-track a sudden bend outward,

as at $1\frac{1}{2}$, so that as the inner wall impinges upon the roller the tucker will be thrown to the position shown in Fig. 7. The knotter should remain in this position until the knotter has full control of the strands of twine, or at least has the knot formed, when it may be removed.

The operation of the knotter in forming the knot by a rotation on its axis is precisely like that well understood, and need not be further described, other than to speak of the positions of the strands of twine when the tucker withdraws and the stripping-arm K approaches. When the knotter comes to rest, the loop of the knot encircles the transverse jaws, and the strands of twine that are to form the bow are held between them and ready for the completion of the knot by the forcing of the loop over the bow and off the jaws by stress in the proper direction applied to the band-twine. The incline $2\frac{1}{2}$ in the cam and gear wheel now effects the removal of the tucker to the position shown in Fig. 1. The twine-cutting and knot-discharging arm, as stated, revolves on the stud-bolt C as an axis, and, from preference, I make them as one piece with the sleeve L, providing the latter with the wing L⁵ and riveting the arm thereto. The arm is so located and its radial sweep is such that at the instant that the knotter has done its work and the tucker has withdrawn from across the slot E⁴ the edge of the arm K' cuts across the axis of the knotter between the latter and the breast-plate, engaging the twine and suddenly changing its direction to such a position in relation to the knotter that the stress on the twine incident to the expansion of the bundle shall be effectual in stripping the knot off from the jaws, at the same time completing it by drawing the loop over the bow.

Referring to Fig. 7 it is seen that the blade K² of the knife is somewhat in advance of the stripping-arm K'; hence, of course, the twines drawn between the holder and knotter will be severed just before the knot is free from the knotter. After the completion of the operation of discharging the knot the tucker may be brought to its position for stopping the new twine laid across the jaws of the knotter from escaping into the slot E⁴. For this purpose I give the cam-track the outward throw $3\frac{1}{2}$, which, acting upon the short arm J', rocks the tucker to the position shown in Fig. 10.

During the interval of time occupied in tying the knot and discharging the same another operation has been performed, which will next be considered. On the face of the wing L⁵, in proper position to engage the teeth of the cord-holder pinion H², is a single tooth L⁶, properly beveled and adapted to engage the teeth of the pinion and thus move the holding-disk. I use a single tooth, and hence advance the pinion but one tooth at a time, and, the number of notches in the disk corresponding with that of the teeth at each pas-

sage of said single tooth, a new notch is presented to receive the twine.

All of the movements have now been described, and it is seen that such movements have been made by parts combined as one piece, the proper timing of the movements being due to proper radial arrangements of the cam, segment, and other parts. As means for locking the pinion in any position to which it may be advanced by the single toothed segment, I provide a flange M on the sleeve L in such a position that it shall be intersected by the axis of the holding-disk pinion, of such diameter and thickness that its periphery shall move, close fitting, between the extensions H' of the teeth H². It is clear that with the parts in the positions shown in Fig. 2 no movement of the pinion can take place. To permit rotation of the holder at the proper interval, the disk or flange M is cut away, as seen in Fig. 7, to form a notch of width slightly greater than the diameter of the circle described by the rotation of the extensions H' of the pinion. The tooth L⁶ is so placed that at the time the twine is fully laid into the notch of the holder the said tooth shall engage a tooth of the pinion. At the same instant the edge M² of the flange M has passed beyond the space between the teeth and set the pinion free, which moves as long as the tooth L⁶ remains in contact; but when the tooth has ceased to move the pinion, the latter having fully assumed its new position, the edge M' of the flange passes in between a succeeding pair of the teeth H', and the holding-disk is again locked.

By the use of the miter-gears A³ and L⁸, the former keyed to the shaft A and the latter cast upon the sleeve L, I am enabled to rotate the mechanism that gives motion to the knotter, tucker, cutter, holder, and stripper on such a plane that the knotter may be driven by spur-segment and pinion rather than by bevels, and to vibrate the tucker on a plane at a right angle to the axis of the knotter, and to move the holder by the same rotating parts.

The bundle-discharging arms I locate on the shaft A and make them of such length that they shall overreach the breast-plate and remove the completed bundle in the usual manner.

I claim—

1. The rotary knotter mounted in a stationary bearing and provided with the stop-pinion, in combination with the stop-motion gear engaging said pinion, the gear-shaft parallel with the axis of the knotter, and the stripper-arm secured to the gear-shaft and adapted, as shown, to extend beyond and sweep over the end of the knotter, and the knife secured to said stripper.

2. The rotary knotter provided with a stop-motion pinion, in combination with the parallel shaft provided with the stop-motion gear engaging the pinion, and with the stripper-

arm adapted to extend across and sweep over the outer or under face of the knotter.

3. The knotter provided with the stop-pinion, and adapted to form the knot by a revolution on its axis, and the cord-holder, all combined with the segment L², the arm K', knife K², and rack L³, all revolving on a common axis, substantially as described.

4. The combination, with the knotter-driving shaft A, of the knotter F and the revolving knife K², arranged on axes substantially parallel with each other and provided with the cord-holder disk H, located between the axes and operated by means of pinion H², having stop-teeth H', tooth L⁶, and notched flange M, revolving on the same axis with the knife, substantially as described.

5. The combination, with the knotter F and the revolving knife K², arranged on axes substantially parallel with each other, of the cord-holder disk H, placed between the knotter and the axis of the revolving knife and operated by means of the pinion H², and tooth L⁶, revolving on the same axis with the knife, substantially as described.

6. The knotter, the breast-plate having the slot with the lateral extension E⁴ to permit the discharge of the knot from the knotter, combined with the tucker having the supplemental finger J⁵, substantially as described.

7. The knotter and its delay-pinion, in combination with a driving-gear L', with the gear-segment and delay-surface to impart complete intermitting rotations to the knotter, the driving-gear shaft L, parallel with the axis of the tyer, the cord-holding disk with the series of

peripheral notches therein, the disk-operating pinion H, and the pinion-extension H', having the series of cross-slots therein, the rack-arm L⁵, carried by shaft L and adapted to give partial rotation to the pinion and disk, and the notched disk M, also carried by the shaft L, whereby the differential rotations are imparted to the knotter and the disk.

8. The knotter-frame having the sleeve B', the stud-bolt C, at a right angle thereto, the shaft A, having the gear A³, the sleeve carrying the mechanism for giving motion to the parts, and the gear L⁸, all combined substantially as described.

9. The knotter-frame and the breast-plate, combined with the connecting stud-bolt C, said bolt adapted to form an axis for the mechanism for moving the various parts substantially as described.

10. In combination with the rotary knotter and its stop-pinion and the adjacent cord-holder, a shaft parallel with the axis of the knotter, the knotter-driving pinion on said shaft, and the arm K, attached to said shaft, its outer end extended in the plane of rotation to sweep over the end of the knotter and strip the knot therefrom, and the knife secured to said arm at a distance from its end at substantially right angles to the plane of rotation, whereby it is adapted to pass between the knotter and holder.

OLE O. STORLE.
